UNITED STATES PATENT OFFICE

2,434,130

ELECTRIC FAN UNIT

Howard B. Turner, Fostoria, Ohio

Application September 5, 1945, Serial No. 614,533

1 Claim. (Cl. 230—273)

1

The invention relates to an electric fan construction, and more especially an electric fan unit and universally adjustable electrical mounting thereof.

The primary object of the invention is the provision of a structure of this character, wherein the fan and motor unit has a universally adjustable electrical separable plug adapted to fit an electric service socket, so that the unit can be operated by electric current and may be adjusted to any selected position through the plug for directing air supply from the unit in any desirable direction, the structure being novel in its make-up and is unique in the arrangement of the parts thereof.

Another object of the invention is the provision of a structure of this character, wherein the hub portion of the bladed fan wheel is rendered elastic, so that it can be applied firmly to a rotor for the drive shaft of the motor, the hub portion being telescoped over the rotor with snug fitting thereon, the motor casing and the hub portion of the wheel having reversely tapered formations, thus giving to the unit a stream-line set up.

A further object of the invention is the provision of a structure of this character, wherein the assembly of the same is novel in its entirety, and is possessed of few parts, these being readily accessible, thus economical for repairs and replacements.

A still further object of the invention is the provision of a structure of this character, which is simple in construction, thoroughly reliable and efficient in operation, strong, durable, readily and easily adjusted with dispatch, neat in appearance, and inexpensive to manufacture and install.

With these and other objects in view the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a side elevation of the structure in accordance with the invention.

Figure 2 is a view similar to Figure 1, and on an enlarged scale, partly broken away.

Similar reference characters indicate corresponding parts throughout the several views in the drawing.

Referring to the drawing in detail, the structure constituting the present invention, comprises a motor casing 10 which has its rearmost shell 11 outwardly tapered, and within this casing is an

electric motor assembly 12 provided with a driving shaft 13, centrally located and extending forwardly from the casing. This shaft 13 has a forward nut carrying tip 14 to which is fastened by the nuts 15 a substantially cone-shaped rotor 16, the forward end 17 of which is closed, excepting a clearance for the tip 14, while the innermost end 18 is fully open.

The shell 11 at its outermost small end has built therewith an externally threaded annular nipple 19, providing interiorly thereof a ball seat or socket 20, the nipple threads being indicated at 21, and detachably connected to this nipple 19 is a coupling collar 22 for a transversely split two-part ball joint forming a universal knuckle head 23, for socketing in the seat or socket 20, the parts 24 and 25, respectively, being held together for separation, and retained in the socket 20 by the collar 22, as is best seen in Figure 2 of the drawing.

The shell 11 is movably keyed at 26 to the part 24, which has assembled therewith the electric current wires 27 leading from spring finger contacts 28 to the motor 12, the contacts 28 being mounted on the part 24 and are adapted for separable engagement with companion spring contacts 29 socketed in the part 25, which latter has unitary therewith an extension plug 30, adapted to be threaded into an ordinary light socket fitting 31 for electrical connection of the motor leads to an electric current supply or current source of a wiring system, not shown.

On the rotor 16 is engaged through telescopic fitting thereover is the elastic hub portion 32 of a bladed fan wheel, the blades 33 of the same being radially extended from this hub portion and angled to the axis of the wheel, as is usual, for air circulation. The hub portion 32 is correspondingly shaped to the rotor and at its open inner end is provided with an inturned annular flange 34 which overlaps the open end 18 of such rotor for the securing of the portion 32 thereon, as is clearly shown in Figure 2 of the drawing, while the outer end 35 of this portion 32 is closed to conceal the fastening of the rotor on the motor shaft.

It will be apparent that the knuckle head 23 permits the fan casing 10 to be adjusted with ease and dispatch, and this adjustment can be held by tightening the collar 22 on the nipple 19.

It is of course understood that changes, variations and modifications may be made in the invention as fall properly within the scope of the appended claim, without departing from the

spirit of the said invention or sacrificing any of its advantages.

It is believed that the construction and manner of operation of the structure will be clearly understood from the foregoing description, without departing from the scope thereof, and therefore a more extended explanation has been omitted.

What is claimed is:

An electric fan unit, comprising an electric motor assembly having a rear-end ball joint 10 socket, a fan wheel driven by said assembly, an electrical socket-plug for separable connection to an electric current supply outlet socket, and having a separable ball fitting for the motor assembly ball joint socket, and means detachably fit- 15

ting the assembly at the socket therein for embracing the ball fitting to hold it in the joint socket and against separation in itself.

HOWARD B. TURNER.
